(57) **CLAIM**

The ornamental design for a dental manual driver, as shown and described.

DESCRIPTION

FIG. 1 is a perspective view of a dental manual driver, showing our new design;

FIG. 2 is a top elevational view thereof, the opposite side being a mirror image;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a partial cross-section along the plane of lines VII—VII of FIG. 3 with a sleeve removed and showing a dental drill in phantom; and,

FIG. 8 is a perspective view of the dental manual driver of FIG. 1, showing a dental drill in phantom.

The dental drill shown in broken lines in FIGS. 7 and 8 is only for the purpose of illustrating the environment in which this invention is used, and forms no part of the claimed design.
